SCRAPING IMPLEMENT

Ernest William Defries, Toledo, Ohio, assignor to The Siegler Corporation, Centralia, Ill., a corporation of Delaware

Filed Mar. 4, 1959, Ser. No. 797,220

3 Claims. (Cl. 15—236)

This invention relates generally to a scraping and cleaning device and more particularly to such a device which is capable of scraping and cleaning contoured and irregular surfaces.

Those irregular or contoured surfaces which do not clean easily provide a difficult cleaning problem. Devices which are sufficiently rugged to accomplish the job are generally too rigid to be accessible to all of the object being scraped.

One object of the present invention is to provide an improved scraper and cleaner which is capable of scraping and cleaning contoured and irregular surfaces.

A further object is to provide such a device which does not become clogged or imbedded with the material being worked with.

A still further object is to provide such a device which is rugged and durable, as well as economical.

Further objectives will be evident from the following specification.

In the drawings:

Figure 1 is a plan view of a scraper formed in accordance with the present invention;

Figure 2 is a side view of the scraper illustrated in Figure 1;

Figure 3 is a perspective view of the wedge shaped securing block used in the scraper illustrated in Figures 1 and 2;

Figure 4 is a fragmentary perspective view of the coiled blade used in the scraper illustrated in Figures 1 and 2 assembled into the wedge-shaped securing block; and

Figure 5 is a fragmentary perspective view of the inner end of the scraper handle.

The scraping and cleaning device of the present invention comprises multiple flexible scraping loops held in a securing block and a handle which removably holds the securing block. The securing block holds the loops so as to maintain adjacent loops spaced from one another.

One embodiment of the invention is shown in Figures 1 through 5. It comprises a handle 2, and a scraping portion or coil 3 consisting of a flexible blade 4 wound in the shape of a spiral. A wedge-shaped securing block 5, with grooves 6 cut into it for tightly holding the coil 3 and also for maintaining space between the adjacent loops 7 thereof, fits firmly but removably into a mating recess 8 in the inner end 22 of the handle 2. The block 5 is held in the handle 2 by a suitable fastener 9.

More specifically, Figures 1 and 2 show a blade 4 which is wound into a coil 3. The blade 4 is a flat, elongated strip of metal, plastic or other suitable tough flexible material such as may be coiled into a spiral of a convenient number of loops. The blade 4 may be serrated along either or both edges.

A block 5 tightly holds the coil 3 with each loop 7 thereof individually secured at radially aligned portions. As shown particularly in Figure 3, the block 5 is generally rectangular in shape, with its two short sides 10 and 10' slightly tapered toward the top 11 to form a wedge. Spaced parallel grooves 6 with their width 12 approxi-

2

mately equal to the thickness 13 of the blade 4 extend parallel to the short sides 10 and 10' across the top of the block 5 and downwardly into it a depth 14 approximately equal to the width 15 of the said blade 4. Perpendicular to the parallel grooves 6 of generally the same width and depth and running through the center of the block 5 is a cross groove 16. As shown in Figure 1, the individual loops 7 of the coil 3 are spaced from one another and sequentially press fitted into the spaced parallel grooves 6. The ends 18 and 18' of the coil are bent at right angles so as to fit into the cross groove 16 thereby assisting in holding the coil in the grooves 6 of the block.

The assembly of the block and coil are removably held by a handle 2. As shown particularly in Figure 5, the handle 2 has a wedged-shaped mating recess 8 formed by tapered sides 20 and 20' at its inner end 22 which snugly but removably receives the wedge-shaped block 5. The original longitudinal dimension of the top of the block, increased by expansion thereof when the coil loops 7 were press fitted into the grooves 6, is restored by the wedging action when the block is removably secured into the mating recess in the handle. A firmer gripping of the loops 7 within their respective grooves 6 preventing sliding therein is thus achieved.

When the block is assembled into the handle the parallel grooves 6 in the block extend at right angles to the axis of the handle. The recess 8 in the handle extends upwardly into it from its underside, and has a depth such that when the block is inserted, the under surface of the block and the under surface of the handle approximately coincide. Also, the width 24 of the block and of the inner end 22 of the handle are the same so that when the device is assembled the side surfaces 26 and 26' of the block and 28 and 28' of the handle end form generally flush surfaces.

The block is held in the recess 8 by a thumb screw 9 which passes downwardly through a clearance hole 30 in top of the handle end 22 and threads into a tapped hole 32 in the top of the block. When the block and the handle are assembled the clearance hole 30 and the tapped hole 32 are axially aligned to receive the screw 9. The handle is suitably formed to facilitate firm and comfortable gripping.

In operation the scraper is gripped by the handle, tilted downward slightly, and while the portions of the scraping loops farthest from the user are held firmly down upon the object 17 to be scraped, it is pulled over the object. The operation is then repeated as many times as necessary.

Obviously, if there is occasion to use the opposite edge of the blade, the whole device may be flipped over and used thusly, or it may be disassembled, the blade turned in the block, and the device reassembled.

The tilting is desirable in order to allow the shoulder formed by the assembled block and handle to clear the object being scraped. Even if the device is dragged along the surface of that object, the region where the blade is held by the block never comes into contact with that surface. Because of that feature and the close fit between the various parts, accumulation of removed material upon the device is minimized.

Snagging is prevented by the flush surfaces formed by the fit between sides and undersurfaces of the block and handle together with the smooth outline achieved by rounding the external edges which may come into contact with the object being scraped.

The fact that the device may be easily and quickly and simply disassembled provides many advantages. Among others, it makes cleaning easy and facilitates changing or replacing the blade. It also allows reversal of the blade.

It is obvious that numerous variations from the de-

picted embodiment are possible without departing from the invention claimed.

Possible modifications include changes in the numbers, shape or cross section of the grooves and loops; the length or edges of the blade; the spacing or orientation of the grooves; the manner of securing the block to the handle. They also include providing individual concentrically oriented, variably sized loops in lieu of a single coiled blade.

The features of the invention believed novel and patentable are set forth in the following claims.

I claim:

1. A coil-type scraping and cleaning implement suitable for engaging contoured and irregular surfaces comprising a tough flexible blade coiled into a spiral and having its ends bent at approximately right angles, a wedge-shaped securing block with multiple grooves into which the loops of said blade are press fitted, said grooves consisting of multiple parallel grooves for supporting said loops and maintaining them in spaced relation and a groove extending transversely to said parallel grooves for accommodating the bent ends of said blade, a handle suitable for gripping which has a mating wedge-shaped recess at its inner end which receives the wedge-shaped securing block in snug but readily removable wedged engagement, and readily removable means for locking said block in said recess, said loops being held so that the portions thereof held in the said block are maintained in fixed relation to the said handle.

2. A coil-type scraping and cleaning implement suitable for engaging contoured and irregular surfaces com-

prising multiple loops of flexible blade material, a wedge-shaped securing block with multiple grooves into which said loops fit, said block maintaining said loops in spaced relation, a handle suitable for gripping which has a mating wedge-shaped recess at its inner end which receives the wedge-shaped securing block in fixed but readily removable wedged engagement, and readily removable means for locking said block in said recess, said loops being held so that the portions thereof held in the said block are maintained in fixed relation to the said handle.

3. A coil-type scraping and cleaning implement suitable for engaging contoured and irregular surfaces comprising a flexible blade coiled into a spiral, a wedge-shaped securing block with multiple grooves into which the loops of said blade fit, said block maintaining said loops in spaced relation, a handle suitable for gripping which has a mating wedge-shaped recess at its inner end which receives the wedge-shaped securing block in fixed but readily removable wedged engagement, and readily removable means for locking said block in said recess, said loops being held so that the portions thereof held in the said block are maintained in fixed relation to the said handle.
